MECHANISM FOR FEEDING EXPLOSIVE PELLETS TO DETONATOR CUPS

Harry W. Morgan, Phillipsburg, N. J., assignor to
The Canister Company, Phillipsburg, N. J., a
corporation of New Jersey

Application April 19, 1939, Serial No. 268,756

13 Claims. (Cl. 86—45)

This invention relates to mechanism for feeding pellets, one or more at a time, from a lot, to a definite predetermined position with reference to the mechanism. Among the objects of the invention are to provide mechanism:

That handles the pellets throughout gently and delicately without scratching, deformation, or concussion so that the danger of explosion of explosive pellets is eliminated; that is capable of nice adjustments, that has as a primary feeding element a plane-surfaced rotatable dial; that has one or more feeding tracks or channels having openings opposed to the direction of rotation of the dial; that has feeding channels for forming single rows of pellets; that has an agitator for feeding pellets into the channels; that has feeding channels adjoining and overlying a rotating dial; that has a slide transverse to the delivery end of the channels, the slide having a side aperture into a vertical V-shaped groove and a clamp for loosely holding the pellets in the groove which is operable by a cam as the slide protrudes from the slide housing, so that the pellets are carried to a predetermined point outside the housing; that has a pivoted arm held in position by a spring under the V-groove and over the above-mentioned predetermined point, which point may be the axis of a vertically reciprocating frictionally mounted ram adapted to push an explosive pellet, or a plurality of explosive pellets down into a cup, the arm being swingable, when a cup is in position axially below the ram, away from the axis of the ram and the cup against a spring, but remaining beneath the pellets if no cup is in the receptive position, thereby preventing the spilling of an explosive pellet and causing a complete reciprocation of the slide until a receptive cup is in position. The slide may move the V-groove to a plurality of positions successively, opposite the delivery end of each channel, for accumulating a plurality of pellets, one atop the other, which may be simultaneously carried to the predetermined point and rammed down into a receptive cup as a unit.

Heretofore the highly explosive pellets used in detonators have been manually positioned and this device is the first mechanism to load detonator cups mechanically with highly explosive pellets. Factors independent of mechanical operations, such as variation in materials and compositions, sometimes unpredictable, may be anticipated by encasing the entire mechanism in an explosion-proof housing.

Explosive detonator pellets are preferably cylindrical in form, the height being less than the

diameter so that the pellets may be arranged for feeding on to the dial of the device on a tray covered with a plane glass at a height sufficient to keep the cylinders upright as they are fed by a pusher slide.

The device may be operated from a vertical rotatable shaft which turns the dial and two cams, one cam moving a spring-retracted lever to actuate the agitator smoothly, and the other cam actuating a second spring-retracted lever which reciprocates the V-groove slide.

Reference is made to the drawings in which:

Fig. 1 is a plan view showing the slide in the delivery position over a detonator cup.

Fig. 2 is an elevation looking at the delivery side.

Fig. 3 is a vertical section on the line 3—3 of Fig. 1, looking in the direction of the arrows.

Fig. 4 is an enlarged plan of the slide.

Fig. 5 is a section on the line 5—5 of Fig. 4, looking in the direction of the arrows.

Fig. 6 is a section taken on line 6—6 of Fig. 4, looking in the direction of the arrows.

A flat table 10 mounts a casting 11 which has a bushing 12 over a central bore 13 in the table 10. A bearing 14 is secured centrally below the bore 13 to the table 10 by a bolt 15. A gear 16 is secured by a pin 17 to a stub shaft 18 rotatable in the bearing 14. Thru an intermediate 19 and pin 21 the shaft 18 is secured to rotate with a stub shaft 22, the latter rotating in the bearing 12. A shoulder 23 on shaft 22 definitely positions the stub shaft 22 on the bearing 12 and provides an annular seat on the upper side. A reduced end 24 of shaft 23 terminates in a screw-threaded stub 25 adapted for a nut 26. The gear 16 is connected with the power to rotate with the shafting counterclockwise.

A plate 27 is mounted atop the casting 11 above which is secured a corner bracket 28 by screws 31. At the rear a slide housing 29 is mounted on the casting 11.

A shelf 32 for feeding explosive pellets has side walls 33 connected at one side with a circular wall 34 which has an enlargement at the end thru which a screw 35 passes to lock it to the end of the slide housing 29. The other end of the circular wall 34 is secured by a screw 36 to the top of housing 29. The bottom of the wall 34 closely overlies a flat dial or circular disk 37 which is secured by screw 49 to collar 40 and rotates with the stub shaft 22 in a counterclockwise direction. The dial 37 has a smooth polished surface upon which cylindrical pellets are slid-

able with slight frictional resistance as herein-after made clear.

Explosive pellets 105 cylindrical in form but of a height less than the diameter of the pellets are arranged flat on a tray, which is covered with plane glass at a height sufficient to clear the tops but to keep the pellets upright, and the tray is mounted on the shelf 32 adjacent the dial 37 and the pellets may be pushed on the dial by a suitable pusher, manually or otherwise.

A plate 41, closely overlying the top of the dial 37, and having a thickness greater than the height of the explosive pellets, is irregularly shaped in periphery, presenting a circular edge on the side opposing the shelf 32 which develops into an oppositely disposed eccentric curved edge on the other side. On the opposite side the plate 41 is attached by brackets 42 to the top of plate 27 by screws 43. The inner edge of the plate 27 and the outer edge of the plate 41 are bounded by a similar arcuate curve and a divider 44 having similar arcuate curves is centrally positioned between the edges of plates 41 and 27 and supported above the dial 37 by screws 45 thru the brackets 42 to provide an arcuate track or channel 46 and a similar track or channel 47, both a bit wider than the explosive pellets. A plate 48 secured by screws on plate 41 extends out over the dial 37 at a height from dial 37 a bit more than the height of an explosive pellet and prevents a pellet getting atop another pellet. The edge of plate 41 tends to feed the pellets into the opening into channel 47 as the dial rotates, the friction between the top of dial 37 and the bottoms of the pellets being sufficient for this purpose.

An agitator 51 is slidingly secured atop the left end of the divider 44 by two screw and slot connections 52, and has an arcuate finger 53 for agitating the pellets on the dial 37 to facilitate their feed. An L-lever 54 has at the outer end of the longer arm a transverse pin and slot connection 55 with the agitator 51, a pivot mounting 56 on the plate 41, a tension spring 57 tied to the long arm of the lever 54 at 58 and pinned to the plate 41, and the inner end of the short arm of the lever 54 engaging an octagonal cam 58 which therefore continuously agitates the agitator 51 to provide a constant feed into the channels 46, 47 so that the explosive pellets fill the channels in single rows, one pellet contacting another pellet.

The delivery end of the channel 46 has a depression 59 which is as deep as the height of an explosive pellet so that a pellet from channel 47 can be fed on top of a pellet from the channel 46 as will be hereinafter set forth.

A slide 61 is mounted in the housing 29 and in cross section has the form of an inverted trapezium with the sides symmetrical and the adjoining sides of a slot in the housing 29 are similar in form to the sides of the slide but with flat walls partially overlying the slide. This mounting is exact thruout. Exact adjustment of the slot is procured by a flat piece 70 adjustable by set screws 86 in the housing 29. A gentle motion of the slide is procured by means of a superstructure 62 which is slotted for movement of a block 63 therein along the axis of the slide. Opposed countersinks in the end of the superstructure 62 and block 63 mount the ends of a coil spring 64 so that any possible shocks inimicable to explosive pellets are absorbed. A post 65 is mounted in the block 63 and also at the upper end in a slide 66 carried in a tracked re-

cess in one end of an arm 67, the other end of which has a pivotal mounting 68 on an extension of the bracket 28. Intermediate the ends of the arm 67 a bolt 69 supports beneath the arm 5 a rotatable collar 71 the side of which engages the side of a cam 72 fixed on the reduced shaft 24 on the annual shoulder atop shaft 22 by the nut 26. The cam 72 is so shaped as to provide for reciprocating the slide 61 and holding it in 10 various positions for predetermined intervals of time. A tension spring 73 is secured to a post 74 on the top of the arm 67 between the cam 72 and the free end of the arm 67, and to the end of an arm 75 extending from the left end of 15 the slide housing 29. It is obvious that the spring 73 holds the roller collar 71 in continuous engagement with the cam 72.

At the right end the slide 61 supports an extension 76 in the front edge of which is a V-groove 20 vertical slot 77. As clearly shown in Fig. 4 this V-groove slot is open to the channel 47 when the slide is in the proper position at the left or inner end of the slide movement, but as the slide 61 moves left from the discharging position shown 25 in Figs. 1 and 3 it first passes the opening from the channel 46. Requisite time for the movement of a pellet from either channel 46 or 47 into the V-groove 77 is provided by suitable forming of the periphery of the cam 72. As 30 shown in Fig. 1 a set-screw 78 in the end of the slide housing 29 extends thru the arm 75 against which a locking nut 79 may be tightened to exactly position the V-groove 77 with reference to the channel 47 so that no pressure can 35 be exerted on the explosive pellets as they are pushed from the channel 47. At the delivery end of channel 46 a small gate 83 is provided to prevent explosions. The V-groove 77 in extension 76 is made to grasp pellets 105 and to centralize 40 them in the groove. Pellets vary in diameter and with smaller pellets, the pellet following, which slightly enters the V-groove 77 is cammed back into the channel 46 by the radial nose on the clamp block 93. At the same time that the V-groove 77 picks up the second pellet the gate 83 45 closes thus keeping the pellet from being crushed by the sharp corner of the V-groove and causing an explosion. Gate 83 is operated by the spring 82 which is fastened in a groove in the plate 85. 50 A cam 84 secured by screws or otherwise near the periphery and on the bottom of the dial 37 actuates a follower 81 which in turn actuates the spring 82 and the gate 83 as the dial rotates. A pin thru a slot in the follower 81 keeps it in 55 position on the plate 80.

Housing 29 mounts a set screw 87 and locking nut 88 therefor, the inner end of the screw 87 providing a stop to engage the right end of the superstructure 62 on the slide 61 to exactly determine the extreme right position of the slide 61. As shown in Fig. 4 the slide extension 76 has a lateral extension 89 opposite the V-groove 77 and a pin 91, connecting with an axial bore therein locks the left end of a bolt 92. Slidably mounted 65 on the bolt 92 is an L-shaped piece 93 having top and bottom cutaways and permitting the partial rotation of a latch 94 pivotally mounted on a pin 95. Around the bolt 92 is a coil spring 96 which bears against the outside wall of the piece 93 and 70 is adjustably secured at the outer end by lock nuts 97 to exert a gentle pressure on piece 93. It is clear that as the latch 94 moves to the right and passes the wall of housing 29 the eccentric engagement of one end with the extension 89 75 causes it to swing to the position shown in Fig. 1

which allows the spring 96 to push the piece 93 toward the V-groove and to resiliently grip any pellets in the groove and hold them against dropping out of the bottom of the groove as the extension 76 moves outside its housing. The corner of the piece 93 proximate the channels 46 and 47 is rounded to prevent a portion of a following pellet from being broken off and gently forces the pellet back into the channel. When the extension 76 is retracted the latch 94 is cammed by the wall of the housing 29 back into the position shown in Fig. 4 and piece 93 pushed back against the tension of the spring 96 to open up the V-groove 77 wider for the facile insertion of explosive pellets therein. Exact adjustments and gentle action can be maintained thruout.

A flat arm 98 has a pivotal mounting 99 on a part of housing 29 and is yieldably held in the extended position by a spring 101. The flat arm 98 normally engages the bottom of the parts 76 and 93 and the bottom of the V-groove 77 is closed thereby. As detonator cups are pushed by mechanism (not shown) into the receptive position under the V-groove 77 the cup mounting pushes the arm 98 out and away from the V-groove 77 against the spring 101 to permit a ram 102 which has a frictional mounting 103 to descend through the V-groove 77 and press the pellet down into a detonator cup held below the ram 102, but if no detonator cup is in the receptive position, arm 98 is not pushed away by the detonator cup mechanism but remains as a closure of the bottom of the V-groove 77 and the explosive pellets are carried back thru a full reciprocation of the slide 76, or repeatedly, until a detonator cup is in the receptive position, so that no explosive pellets are spilled about the mechanism with resulting danger of explosion.

On the return stroke of the slide 76, or in any other position outside the V-groove 77 the side wall of the slide forms a stop preventing the exit of pellets from the channels 46 and 47. The slide is related to the operating cam so that the V-groove first stops at the delivery end 59 of channel 46 and loads a pellet in the lower part of the V-groove. Then it moves to the delivery end of channel 47 where another pellet 105 is pushed in on top of the first pellet by the action of the dial 37. Both pellets are fixed exactly on each other by the spring pressure of part 93 against the pellets and the V-side of the groove so that they are both axially adjusted and aligned with the axis of the ram 102 in the delivery position.

Variations in details will readily occur to those skilled in the art, in view of my disclosure, but within the spirit and scope of my invention, and I do not therefore limit myself to the exact disclosure.

I claim:

1. A mechanism for feeding pellets comprising, in combination, a rotatable dial, a plurality of channels over the dial and having openings opposed to the direction of rotation of the dial and delivery openings the delivery opening of one channel being lower than that of another, and a slide transverse to the channels, having means for receiving a pellet from each channel successively, and movable to a delivery point outside the dial.

2. A mechanism for feeding pellets comprising, in combination, a rotatable dial, a plurality of channels over the dial and having openings opposed to the direction of rotation of the dial and delivery openings the delivery opening of one

channel being lower than that of another, and a slide transverse to the channels, having a clamp for receiving a pellet from each channel successively and holding them frictionally, one atop the other, and movable to a delivery point outside the dial.

3. A mechanism for feeding pellets comprising, in combination, a rotatable dial, a plurality of channels over the dial and having openings opposed to the direction of rotation of the dial and delivery openings, a slide transverse to the channels, having a clamp for receiving a pellet from each channel successively and holding them frictionally, one atop the other, and movable to a delivery point outside the dial, and an arm normally underlying the slide at the delivery point but movable away from the delivery point.

4. A mechanism for feeding pellets comprising, in combination, a rotatable dial, a plurality of channels over the dial and having openings opposed to the direction of rotation of the dial and delivery openings, a slide transverse to the channels, having a clamp for receiving a pellet from each channel successively and holding them frictionally, one atop the other, and movable to a delivery point outside the dial, and an arm pivotally mounted and underlying the slide at the delivery point and under spring tension and movable against the tension of the spring away from the delivery point.

5. A mechanism for feeding pellets comprising, in combination, a rotatable dial, a channel over the dial and having an opening opposed to the direction of rotation of the dial and a delivery opening, an agitator for feeding pellets into the channel, and means for receiving and positioning the pellets as they issue from the channel.

6. A mechanism for feeding pellets comprising, in combination, a rotatable dial, a channel over the dial and having an opening opposed to the direction of rotation of the dial and a delivery opening, an agitator for feeding pellets into the channel, means for moving said agitator comprising a spring and a rotatable cam, and means for receiving and positioning the pellets as they issue from the channel.

7. A mechanism for feeding pellets comprising, in combination, a rotatable dial, a plurality of channels over the dial and having openings opposed to the direction of rotation of the dial and delivery openings at the opposite end, the delivery opening of one channel being lower than that of the other channel, and a slide transverse to the channels, having means for receiving a pellet from each channel successively, and movable to a delivery point outside the dial.

8. A mechanism for feeding pellets comprising, in combination, a rotatable dial, a channel over the dial and having an opening opposed to the direction of rotation of the dial and a delivery opening, a gate at the delivery opening, means on the dial for operating said gate, and means for receiving and positioning the pellets as they issue from the channel.

9. A mechanism for feeding pellets comprising, in combination, a rotatable dial, means for guiding the pellets on the dial, and a plurality of channels over the dial having receiving and delivery openings for the pellets, the receiving openings being opposed to the rotation of the dial and the delivery opening of one channel being lower than that of another channel, whereby one pellet is fed atop of another.

10. A mechanism for feeding pellets comprising, in combination, a rotatable dial, means for

guiding the pellets on the dial, a plurality of channels over the dial having receiving and delivery openings for the pellets, the receiving openings being opposed to the rotation of the dial and the delivery opening of one channel being lower than that of another channel, and means for making the service of the pellets to said channels selective.

11. A mechanism for feeding pellets comprising, in combination, a rotatable dial, means for guiding the pellets on the dial, a plurality of channels over the dial having receiving and delivery openings for the pellets, the receiving openings being opposed to the rotation of the dial and the delivery opening of one channel being lower than that of another channel, and means for closing the receiving opening of one of the channels without interrupting the feeding of pellets to the other channel.

12. A mechanism for feeding pellets comprising, in combination, a rotatable dial, means for guiding the pellets on the dial, a plurality of

channels over the dial having receiving and delivery openings for the pellets, the receiving openings being opposed to the rotation of the dial and the delivery opening of one channel being lower than that of another channel, and means for automatically interrupting the delivery of the pellets from said delivery openings under given conditions.

13. A mechanism for feeding pellets comprising, in combination, a rotatable dial, a plurality of channels over the dial and having openings opposed to the direction of rotation of the dial and delivery openings, the delivery opening of one channel being lower than that of another, a slide transverse to the channels, having means for receiving a pellet from each channel successively and holding them frictionally, one atop the other, means for reciprocating the slide successively with respect to the delivery openings of said channels, and means for moving the slide to a delivery point outside the dial.

HARRY W. MORGAN.
